UNITED STATES PATENT OFFICE.

RICHARD FEIGL, OF CHICAGO, ILLINOIS.

DESIGN FOR A PUZZLE-BOARD.

SPECIFICATION forming part of Design No. 32,933, dated July 10, 1900.

Application filed May 7, 1900. Serial No. 15,847. Term of patent 3*1*/2 years.

To all whom it may concern:

Be it known that I, RICHARD FEIGL, a subject of the King of Hungary, and a resident of Chicago, in the county of Cook and State of Illinois, have invented a new and original Design for Puzzle-Boards, of which the following is a specification, reference being had to the accompanying drawing, forming a part thereof.

- The drawing shows a perspective view of a puzzle-board made according to my new design.

The leading feature of my design consists in the peculiar arrangement of the arcs and transverse walls connecting the same, and particularly in the arrangement of arcs and connecting-walls shown within the five inner circles outlined by said arcs.

The puzzle-board is made of a flat circular board 1, having a raised peripheral rim 2. A 20 plurality of concentric partitions 3 project above the board 1 within said rim. Each of said partitions is made in the form of an arc. Said partitions are connected by cross-partitions 4. 25

What I claim as new, and desire to secure by Letters Patent, is—

The design for a puzzle-board substantially as herein shown and described.

Signed by me at Chicago, Illinois, this 5th 30 day of May, 1900.

RICHARD FEIGL.
